United States Patent Office

Des. 191,828
Patented Nov. 28, 1961

191,828

GAMEBOARD

Howard S. Garns, 4530 Deven Court, Indianapolis, Ind.

Filed Dec. 7, 1960, Ser. No. 63,139

Term of patent 14 years

(Cl. D34—5)

The figure is a top plan view of my gameboard, showing my new design. The gameboard is of conventional thickness.

I claim:

The ornamental design for a gameboard, as shown and described.
